US0D1099154S

(12) **United States Design Patent** (10) Patent No.: **US D1,099,154 S**
(45) Date of Patent: ** Oct. 21, 2025

(54) **DISPLAY SCREEN OR PORTION THEREOF WITH ICON**

(71) Applicant: **West Shore Home, LLC**,
Mechanicsburg, PA (US)

(72) Inventor: **Elizabeth T. Schwarz**, Savage, MN
(US)

(73) Assignee: **WEST SHORE HOME, LLC**,
Mechanicsburg, PA (US)

(**) Term: **15 Years**

(21) Appl. No.: **29/934,556**

(22) Filed: **Mar. 26, 2024**

(51) LOC (15) Cl. **14-04**

(52) U.S. Cl.

USPC **D14/489**; D14/492

(58) **Field of Classification Search**

(57) **CLAIM**

The ornamental design for a display screen or portion thereof with icon as shown and described.

DESCRIPTION

The FIGURE is a front view of a computer display screen or portion thereof with an icon showing my new design.

The broken lines show the display screen and form no part of the claimed design.

1 Claim, 1 Drawing Sheet
